ELECTRIC FAN.

1,081,244.

Specification of Letters Patent.

Patented Dec. 9, 1913.

Application filed February 23, 1910. Serial No. 545,291.

To all whom it may concern:

Be it known that we, GUSTAVE C. MARX and ADOLPH F. BECKER, citizens of the United States, residing at Elizabeth, in the county of Union and State of New Jersey, have invented certain new and useful Improvements in Electric Fans, of which the following is a specification, reference being had therein to the accompanying drawings.

10 This invention relates to an improvement in that class of electric fans having a stationary base or standard upon which is pivotally mounted the motor-frame carrying the fan-blades and provided with means for 15 communicating a turning movement to the motor-frame upon its support for varying the direction of the air current produced thereby, and the invention has for its primary object to provide a simple and compact 20 train of speed-reducing mechanism for imparting an oscillatory movement of the motor-frame, and which may be readily applied to or removed from the fan when desired.

25 In its most approved form the motor-frame is constructed with a bearing boss for the rearward end of the armature-shaft upon the exterior of which boss is fitted a hub formed in a gear casing which carries a vertical crank-shaft and a horizontal intermediate shaft in transverse relation thereto. The lower end of the crank-shaft beneath the gear-case carries a crank-disk connected by means of a pitman with the supporting standard for the motor-frame, while upon the upper inner end of the crank-shaft is fixed the hub of a crown-wheel whose web is formed with a central cavity to accommodate the lower side of a worm-wheel fixed 35 upon the intermediate shaft and meshing with a worm upon the armature-shaft, a second gear-wheel being fixed upon the intermediate shaft and meshing with the crown-wheel to which it imparts a rotary motion derived from the armature-shaft through 40 the described worm-gearing.

45 The standard is preferably formed in sections having their adjacent portions overlapped and united by means of a transverse clamp-screw, interposed washers with an annular series of corrugations being secured each to its respective section, whereby the loosening of the clamp-screw permits the parts of the standard to be slightly sep-

arated and shifted relatively to change the angle of the section carrying the motor-frame and hence the direction of the air current induced by the fan.

In the accompanying drawings, Figure 1 is a side elevation of a desk fan embodying the present improvements, and showing the rearward armature-shaft bearing boss and the gear case in section to expose the gearing; Fig. 2 is a detached sectional elevation of the gear-case and its contents through the axis of the intermediate gear-shaft; and Fig. 3 a view of the lower face of the crank-disk. Fig. 4 is an elevation upon an enlarged scale showing the sectional standard and its means of adjustment, and Fig. 5 a sectional elevation of the same. Fig. 6 is a detached elevation of one of the sections of the standard, viewed at right angles to Fig. 5. Fig. 7 is a face view and Fig. 8 an edge view partially in section representing one of the corrugated washers for the standard. Figs. 9 and 10 are sectional elevations of a different form of crank-member from that of the preceding figures, and Fig. 11 a transverse section of the same.

The fan is constructed with the usual base or standard 1, intermediate member 2 and socket-member 3 formed in the upper end with an axial aperture entered by the cylindrical stud 4 depending from the body 5 of the motor-frame provided with the front and rear bearing caps 6 and 7 with outwardly extending bosses 8 and 9 in which are journaled the opposite end portions of the armature-shaft 10 carrying upon its forward end the fan-blades 11. The rearward bearing boss 9 is provided with a bushing 12 secured loosely in position by the locking screw 13 and affording the bearing for the rearward end of the armature-shaft.

Upon the cylindrical exterior of the bearing boss 9 is fitted a hub 14 formed in the body 15 of the gear-case which is open at the top rearward of the hub 14 and provided with a removable cover 16 secured in place by means of the screws 17. The gear-case is formed with a depending bearing boss 18 in which is journaled the vertical crank-shaft 19 whose axis is in intersecting relation with that of the armature-shaft. Upon the lower end of the shaft 19 is fixed by means of the transverse pin 20 the hub 21 of a crank-

plate 22 carrying a screw-stud or pin 23 embraced by one end of a link 24 whose opposite end embraces a stud 25 tapped into a lateral lug 26 upon the fixed socket-member 3 or section 3 of the standard.

Upon the upper end of the shaft 19 is fixed by means of the transverse pin 27 the hub 28 of a crown-wheel with toothed rim 29 and dished web 30 affording a gear cavity in the upper face of the crown-wheel embraced by the series of bevel-gear-teeth 29* of the rim.

The gear-case is provided in its opposite walls with alined threaded apertures in which are introduced the socketed threaded inner extremities of the bearing plugs 31 in which are journaled the opposite ends of the intermediate gear-shaft 32 disposed in transverse relation to both the armature-shaft 10 and the crank-shaft 19. Fixed upon the intermediate shaft 32 near one end is the bevel pinion 33 meshing with the crown-wheel teeth 29*, and arranged centrally of the gear-case is the worm-wheel 34 which is pinned upon the shaft 32 and meshes with the worm 35 fixed upon the rearward end of the armature-shaft 10. As will be observed, the cavity in the body of the crown-wheel affords ample clearance space for the lower side of the worm-wheel 34, while permitting the rim 29 of the crown-wheel to be extended into sufficiently close relation with the transverse shaft 32 to establish operative relation with a pinion thereon of a size necessary to transmit thereto rotary motion of the requisite speed for imparting a slow oscillatory motion to the motor-frame upon its pivotal stud 4.

In order to vary the amplitude of oscillation of the motor-frame, the crank-disk 22 is provided as shown in Fig. 3, with several apertures 22* at different distances from its center to receive the stud-pin 23, whereby the throw of the crank-pin 23 is changed. To maintain the motor-frame stationary in case a steady air current is desired in a given direction, the bottom of the shaft 19 is formed with a threaded aperture 19*, as also represented in Fig. 3, into which the stud-screw 23 may be screwed, whereby the link connection between the standard and the crank-shaft will remain uniform.

As represented in dotted lines in Fig. 4, the pivotal stud 4 of the motor-frame is necked at 4*, and the necked portion is entered by a screw 36 tapped into the socket-section 3 for locking the motor-frame revolvably upon its supporting standard; but it is evident that by employment of a screw 36 of sufficient length the latter may be employed to clamp the stud 4 against turning, and the oscillating mechanism, with the gear-case by which it is carried, may be removed and the fan employed in the ordinary manner.

As shown in the drawings, the base section 1 is formed with an axial aperture entered by a depending stud 2* of the intermediate member 2 of the standard which is secured in position by means of the screw 37 with its head countersunk in the same. The intermediate section 2 of the standard is formed with an upwardly projecting wing or disk 38 provided with a transverse threaded socket 39 entered by the threaded end portion of a clamp-screw 40 provided with the head 41 having wings 42 and entering a transverse aperture in the depending wing or disk 43 similar to the disk 38 upon the socket-member 3 of the standard. Each of the disks 38 and 43 is provided with a series of transverse apertures 44, as represented in Fig. 6, to receive the bodies of pins 45 whose outer ends enter similarly arranged apertures 46 in the washers 47 which are formed with central perforations 48 and with annular series of corrugations 49 at their peripheries, as represented in Figs. 7 and 8. One of the washers 47 is applied to the flat face of each of the disks 38 and 43, and secured thereon by riveting or upsetting the ends of the pins 45, as represented in Fig. 5.

As will be readily seen, when the clamp-screw 40 is turned to draw the parts 38 and 43 together, the corrugations of their respective washers 47 interlock and serve to insure against the shifting of the standard-section 3 upon the section 2, but by retracting the clamp-screw 40 slightly, the parts 38 and 43 may be separated sufficiently to enable the corrugations of their respective washers 47 to pass one another, and the members 2 and 3 may thus be shifted into different angular relations measured by multiples of the pitch of the corrugations 49, and thus their extent of adjustment may be determined within a very few degrees, while they may be as securely locked in one as in another relative adjustment and with a very little turning of the clamp-screw 40.

In the modification represented in Figs. 9, 10 and 11, the lower end of the crank-shaft 19 has loosely fitted thereon a collar 50 formed in its upper end with an oil cup or cavity 51 and having below the same a cross-bar 52 with a socket 53 closed at one end and extending lengthwise thereof and intersected by the enlarged lower end of the shaft 19, which is formed with a series of diametrically arranged notches 54. The cross-bar 52 is provided in its lower side with a slot 55 communicating with the socket 53 near its open end, which is entered by the shank of a screw-stud 56 entering a clamp-nut 57 within the socket and having surrounding its outer portion a bushing 58 adapted to be embraced by one end of the link 24. The collar 50 is secured in position upon the enlarged lower end of the shaft 19.

by means of a washer 59 in practice riveted upon the latter. The normally closed inner end of the socket 53 has an axial aperture through which passes the coupling pin 60 provided upon its outer extremity with a knurled head 61 fixed thereon and provided with a transverse rib 62 adapted to enter a similarly arranged groove 63 in the adjacent end of the cross-bar 52. The inner end of 10 the pin 60 is fitted to and adapted to enter the apertures or notches 54 of the shaft 19, and such pin is pressed toward the latter by means of a spring 64 interposed between the closed inner end of the socket 53 and a 15 thrust-collar 65 fixed upon the pin 60 near its inner end. By retracting the pin 60 to disengage its point from one of the apertures 54 of the shaft 19, and turning the pin so that the transverse rib or tongue 62 is 20 out of register with the groove 63 of the cross-bar 52, the point of the pin is maintained sufficiently retracted to enable the shaft to turn without imparting a corresponding movement to the cross-bar and 25 consequently to the crank-pin 56 for oscillating the fan-motor, but by turning the knurled head 61 of the pin from inoperative position represented in Fig. 11 to operative position represented in Fig. 10, the pin is 30 enabled to resume operative relation with the apertured lower end of the crank-shaft 19 under the action of its spring 64. While a single aperture 54 would be sufficient to insure the coupling of the collar 50 and cross- 35 bar 52 to the shaft 19 under the action of the spring 64, the provision of a series of such apertures insures the more prompt action of the coupling pin 60 under the action of its spring.

40 The employment of a detachable gear-case containing the driven train of speed-reducing mechanism is a feature of the present improvement of considerable importance, as it not only enables the fan-oscillating mechanism to be applied and removed at will, but enables the fan-motor and its casing to be constructed as usual regardless of whether or not the oscillating feature is to be embodied in the structure. In practice the 45 gear-case hub is secured in position upon the boss 9 of the motor-frame by means of a setscrew, but any usual or suitable means may be provided for such purpose. While the gear-case may be used or not, as conditions 50 may require, when applied to the motor-frame it constitutes a removable part of the same and forms a rigid part of the framework in which are journaled the armature-, intermediate- and crank-shafts. As the hub 55 55 of the gear-case serves to accurately locate the intermediate shaft 32 with relation to the armature-shaft 10, and as the crank-shaft 19 with the concave-webbed crown-wheel carried thereby has its axis in intersecting relation with that of the shaft 10

and hence of the hub 14, it is evident that the gear-case 15 may be applied interchangeably to the hub of any fan provided with a suitable boss with the certainty that the driving and driven members of the train of speed-reducing gearing will be disposed in the proper relation for efficient coöperation

70 While the form of the crank-disk represented in Fig. 3 is the simpler, it will be found preferable in many cases to employ a carrier loosely mounted upon the lower end of the crank-shaft and provided with a coupling pin for establishing and interrupting operative connection between the crank-shaft and the standard, as represented in Figs. 10 and 11, whereby the fan may be 75 instantly converted from the oscillating variety to one in which the direction of the induced air current remains constant. In practice, the gear-case 15 serves not only to inclose the gearing and exclude dust and dirt therefrom, but to hold grease, which is commonly of a more or less plastic consistency, in which the lower portion of the mechanism is submerged. As the crown-wheel 29 and worm-wheel 34 partially embraced thereby have different planes of rotation, the grease is continually stirred, so that the worm-wheel is not permitted to cut for itself a path in the grease and thereafter 80 operate in conjunction with the worm 35 without carrying the necessary lubricant to insure smooth running of such interengaging parts.

85 Having thus set forth the nature of the 100 invention, what we claim herein is:—

1. In an electric fan, having a shaft, a 105 motor, a motor casing provided with bearings for rotatably supporting said shaft at both ends, and a standard on which the motor casing is pivotally mounted, a fan-oscillating unit, including a gear-case having means for removably attaching it to the motor casing, a train of gearing therein, means for separably connecting said train of 110 gearing with the fan shaft, and means for separably connecting said train of gearing with the standard, whereby said fan-oscillating unit is adapted to be detached from the motor casing without affecting the operativeness of the fan independently of the fan-oscillating unit.

115 2. An electric fan, having a shaft, a motor, and a motor casing in which said shaft is supported at both ends, and a standard on 120 which the motor casing is pivotally mounted, combined with a fan-oscillating mechanism, comprising essentially a gear-case provided with means for attaching it to and removing it from the motor casing without 125 affecting the support of the fan-shaft, and a train of gearing connected with the standard and adapted to be operatively connected with the fan-shaft.

130 3. In an electric fan, in combination, a

motor-frame provided with a projecting bearing boss, a standard upon which said motor-frame is pivotally supported, a motor comprising an armature-shaft journaled in 5 said bearing boss, a gear-case adapted to be removably fitted to and secured upon said bearing boss, speed-reducing gearing mounted within said gear-case and adapted to be operatively connected with the armature-shaft, and an operative connection between 10 said speed reducing gearing and the supporting standard whereby the motor-frame is oscillated upon the standard, the said gear-case and its contained gearing being 15 adapted to be removed from the motor-frame without interfering with the operation of the motor.

4. In an electric fan, in combination, a motor-frame, a standard upon which said motor-frame is pivotally supported, a motor 20 comprising an armature-shaft journaled in said motor-frame, a crank-shaft supported by the motor-frame upon an axis in intersecting relation with that of the armature-shaft, an operative connection between said 25 crank-shaft and the standard, an intermediate shaft between said armature- and crank-shafts and mounted upon the motor-frame in transverse relation to both of said 30 shafts and in axially intersecting relation with said crank-shaft, and a train of speed-reducing gearing connecting said intermediate shaft with the armature- and crank-shafts and comprising a worm on the armature-shaft, a worm-wheel on the intermediate shaft meshing with said worm and a 35 pinion also mounted upon the intermediate shaft and spaced from said worm-wheel, and a concaved crown-wheel fixed upon the

crank-shaft and having its teeth surrounding said worm-wheel and in mesh with said pinion. 40

5. In an electric fan, in combination, a motor-frame, a standard upon which said motor-frame is pivotally supported, a motor 45 comprising an armature-shaft having a worm thereon and journaled in said motor-frame, a crank-shaft supported by the motor-frame upon an axis in transverse relation with that of the armature-shaft, an 50 operative connection between said crank-shaft and the standard, an intermediate shaft between said armature- and crank-shafts and mounted upon the motor-frame in transverse relation to both of said shafts, 55 a worm-wheel mounted upon said intermediate shaft and meshing with the worm on the armature-shaft, a crown-wheel having a hub fixed upon the crank-shaft, a toothed rim disposed adjacent to the intermediate 60 shaft and surrounding said worm-wheel, and a concaved connecting web into which said worm-wheel extends, a pinion mounted upon the intermediate shaft and meshing with said crown-wheel, and a casing closed 65 at the bottom and surrounding said worm-wheel, crown-wheel and its operating pinion and adapted to hold a supply of lubricant in which the latter operate.

In testimony whereof, we have signed our 70 names to this specification, in the presence of two subscribing witnesses.
